COMBINED CRIB AND WARDROBE

George R. Barrett, Minneapolis, Minn.

Application September 26, 1946, Serial No. 699,443

6 Claims. (Cl. 5—2)

1

My invention relates to an improvement in combined crib and wardrobe wherein it is desired to provide an article of furniture which may be used to contain clothing or the like and which may also conceal a baby's crib.

Homes in which no small children reside are seldom equipped with a crib which is instantly available for use. Such cribs are only used at intervals. As a result when the services of a crib are required, considerable difficulty is usually involved in locating one and in erecting it for use by guests. This difficulty is particularly noticeable in tourist homes, hotels and the like where the presence of guests is commonplace.

It is the object of the present invention to provide an article of furniture which may serve the double capacity of a storage space for clothes and the like and also a storage space for a crib. When in enclosed position the crib is similar in appearance to a chest of drawers or a wardrobe of a conventional type. However, when desired the crib may be moved laterally to project to one side of the wardrobe in which position it may be readily used.

A feature of the present invention resides in the fact that the crib is slidably supported for movement out of the wardrobe in either direction therefrom. As a result my combined article of furniture may be located in any desired position and the crib may be withdrawn therefrom from either side thereof.

A feature of the present invention resides in the fact that my wardrobe is provided with drawer space for use in storage of clothing and the like. I have found that a relatively small drawer space is usually sufficient to serve the needs of the usual guests. Therefore by taking up a part of the usual drawer space for the accommodation of a crib, I am in reality not detracting materially from the effectiveness of the wardrobe.

A feature of the present invention resides in the provision of a cross member mounted above the crib near each side of the wardrobe. The top of the crib engages against this cross member when weight is placed within the crib, thereby permitting the crib to be maintained in a substantially horizontal position projecting from either side of the wardrobe.

These and other objects and novel features of my invention will be more clearly and fully set forth in the following specification and claims.

In the drawings forming a part of my specification:

Figure 1 is a perspective view of my combined

2

crib and wardrobe showing the construction thereof.

Figure 2 is a sectional view vertically through the wardrobe shown in Figure 1.

5 Figure 3 is a sectional view through the wardrobe on a plane substantially parallel to the front of the wardrobe.

Figure 4 is a cross sectional view through the crib.

10 Figure 5 is a perspective view of a clamp which is usually provided on the rear of the wardrobe.

The combined crib and wardrobe A includes a substantially rectangular cabinet illustrated in general by the letter B and a slidable crib designated in general by the letter C. The crib C may be generally concealed within the wardrobe cabinet B or may be moved to project from either side thereof as indicated in Figures 1 and 3 of the drawings. The cabinet B includes rectangularly arranged corner pillars or posts, the front posts being indicated by the numerals 10 and 11, while the rear posts are indicated generally by the numerals 12 and 13. These posts support the cabinet top 14 which may serve as a shelf or table top in the usual manner.

15 A rectangular frame comprising the front and rear frame members 15 and 16 and the side frame members 17 and 19 extend between the legs or posts 10, 11, 12 and 13 immediately beneath the table top 14. A similar rectangular frame is provided near the lower ends of these legs, the lower frame member including the front and rear frame members 20 and 21, and the side frame members 22 and 23. A back panel 24 20 extends from the top frame member 16 to the lower frame member 21 and from the leg 12 to the leg 13 closing the rear of the cabinet.

An additional rectangular frame is provided at a point spaced below the upper frame described.

25 40 This third frame includes the front frame member 25 which extends between the front legs 10 and 11, the rear frame member 26 which extends between the rear legs 12 and 13 inwardly of the panel 24, and side frame members 27 and 29.

45 45 A panel 30 extends from the top frame 17 to the frame member 27 between the side legs 10 and 12. A similar panel 31 extends between the frame members 19 and 29 and between the side legs 11 and 13. These panels 30 and 31 close the sides 50 55 of the cabinet B near the upper extremity thereof.

An additional frame is provided spaced above the lowermost frame member. This last mentioned frame includes a front frame member 32 extending between the front legs 10 and 11 and a rear frame member 33 extending between the

rear legs 12 and 13. This latter frame also includes a pair of transversely extending guides or tracks 34 and 35 supported inwardly of the frame members 32 and 33. The latter mentioned frame also includes a side frame member 36 which extends from the leg 10 to the leg 12 and a side frame member 37 which extends between the legs 11 and 13. A panel 38 is provided between the frame member 36 and the frame member 22 between the side legs 10 and 12. A similar panel 40 is positioned between the frame members 37 and 23 from the front leg 11 to the rear leg 13. A compartment bottom closure 41 is supported by the track members 34 and 35 and by the frame members 36 and 37, as best illustrated in Figures 2 and 3 of the drawings.

A drawer frame is provided between the uppermost pair of frames described. This drawer frame includes a front member 42 between the legs 10 and 11, a rear frame member 43 inwardly of the back panel 24 and side frame members 44 and 45. A center partition 46 is likewise provided connecting the front member 42 with the rear frame member 43. A pair of transversely spaced drawers 47 and 49 are mounted on the drawer frame on opposite sides of the central partition 46, these drawers 47 and 49 being slideable forwardly in the manner best illustrated in Figure 1 of the drawings.

A drawer 53 is slidably supported upon the lowermost frame members 20, 21, 22 and 23 and is slideable forwardly into open position in the manner illustrated in Figure 1 of the drawings. All of the drawers 47, 49, 50 and 53 operate in the usual manner.

A pair of bearing members 54, and 55 extend from the front frame member 25 to the rear frame member 26 to act as a bearing plate for the upper surface of the crib as will be later described in detail. The crib C is slideable beneath these bearing plates 54 and 55 in the transverse movement of the crib into or out of the cabinet B.

The crib C is constructed as is best illustrated in Figures 1 and 4 of the drawings. Each end of the crib includes a rectangular end frame 56 which is closed by means of an end closure panel 57. The rectangular frames 56 are connected by a pair of spaced top rails 59 and a pair of similarly spaced bottom rails 60. The rails 60 are designed to rest upon the guides or tracks 34 and 35 which are closed so as to hold the rails 60 in proper position during transverse movement of the crib. A diagonally extending brace 61 extends across the bottom of the crib. A rectangular frame 62 rests upon this brace 61 and acts to support the crib mattress. The rectangular frame 62 is provided with spaced slats 63 on which the mattress may rest.

As best seen in Figures 1 and 3 of the drawings spaced slats or bars 64 extend from the top frame members 59 to the corresponding bottom frame members 60. These slats 64 prevent the infant from rolling from the mattress while resting thereupon.

A lamp 65 is preferably provided on the cabinet top 14 near the rear edge thereof. A cord which is provided extends from this lamp, the end of this cord being normally wrapped about a cleat 66 on the rear panel 24. This cleat 66 permits the wire to be properly supported during movement of the article of furniture and permits its ready portability.

The operation of my combined crib and wardrobe is believed obvious from the foregoing de-

scription. When the crib is not desired for use, it is normally contained within the wardrobe, the end panels 57 thereof being substantially aligned with the side panels of the wardrobe. Thus in appearance the combined crib and wardrobe is almost identical to that of that of a chest of drawers of common make. When a crib is required it is only necessary to pull the crib C from one side or the other of the cabinet B, a pull ring such as 67 being provided on the end panels 57 for this purpose. When mostly withdrawn from the cabinet B the end frame 56 on one end of the crib engages beneath the cross member 55, this member acting as a bearing plate to hold the projecting end of the crib from tilting downwardly. Considerable weight may be placed in the crib without danger of having the crib become accidentally disengaged from its supporting cabinet.

For the purpose of convenience I have described the member C as a crib which would indicate that it is solely for use as a bed for children. Actually the member C could also be used as a play pen for infants, the walls thereof serving to confine the infant to a relatively small area. In such an event the crib C may be entirely removed from the cabinet B if it is so desired and placed upon the floor or any other suitable support.

The crib C is normally concealed from the floor of the cabinet B by the floor panel 69. This panel is equipped with decorative strips 70 dividing the panel into sections to conform with the appearance of the remainder of the cabinet. By thus dividing the panels 69 the front of the cabinet looks very much like a chest of drawers when the drawers are closed and the crib is in enclosed position.

In accordance with the patent statutes, I have described the principles of construction and operation of my combined crib and wardrobe, and while I have endeavored to set forth the best embodiment thereof, I desire to have it understood that this is only illustrative thereof, and that obvious changes may be made within the scope of the following claims without departing from the spirit of my invention.

I claim:

1. A combined crib and wardrobe comprising a substantially rectangular cabinet having an opening in each of two opposed sides, and a crib slidably supported by said cabinet and movable through either of said openings to project from either side of said cabinet, the ends of the crib forming closures for said openings when the crib is contained therein.

2. A combined crib and wardrobe comprising a rectangular cabinet, side panels on said cabinet, an open side wall portion adjacent each of said panels, a crib slidably supported by said cabinet, said crib having end panels substantially aligned with said side panels of said cabinet in closed position of said crib, and side panels on said crib connecting said crib end panels.

3. A combined crib and wardrobe comprising a substantially rectangular cabinet, side panels thereupon, front and rear panels thereupon, said side panels being relatively small and providing side openings in said cabinet, a crib mounted in said cabinet for lateral slideable movement, substantially parallel slatted sides on said crib normally concealed by said front and rear panels of said cabinet in closed position of the crib, and end panels on said crib normally aligned with said side panels in closed position of said crib.

4. A combined crib and wardrobe comprising a rectangular cabinet, a drawer slidably supported thereby for movement forwardly and rearwardly in said cabinet, side wall panels enclosing the sides of said drawer, a front and rear panel on said cabinet, said side walls being open adjacent said front panel, an open topped crib laterally slidable in said cabinet, the drawer forming a top closure for the crib when within said cabinet, and end wall panels on said crib normally substantially aligned with said side panels of said cabinet when said crib is in closed position.

5. A combined crib and wardrobe including a rectangular cabinet body, transverse guides therein, openings in each of two opposed sides of said crib, a crib slidably supported on said guides and projectable from either side of said cabinet, the ends of the crib forming closures for said openings when the crib is contained therein, and means in said cabinet body above the end of the crib retained within the cabinet body in projecting position thereof to support the crib as a cantilever.

6. A combined crib and wardrobe comprising a substantially rectangular cabinet having an

opening in each of two opposed sides, a crib slidably supported by said cabinet and movable through either of said openings to project from either side of said cabinet, the ends of the crib forming closures for said openings when the crib is contained therein, and means in the cabinet body supporting said crib as a cantilever in projecting position thereof.
